HAIRPIN CLIP

Carl W. Renstrom, Omaha, Nebr., assignor to
Tip-Top Products Company, Omaha, Nebr., a
corporation of Nebraska

Application July 25, 1949, Serial No. 106,681

7 Claims. (Cl. 132—46)

1

This invention relates to hairpin clips, particularly to hairpin clips of the helical spring type, adapted to retain locks of human hair in curled or other form and also adapted for general use as a clip or clamp.

It is an object of the present invention to provide a simplified and improved hairpin clip of durable and rigid construction, adapted to be manufactured at low cost from an integral length of resilient wire.

It is a further object of this invention to provide a hairpin clip which may be manipulated and used with ease and comfort, and without damage to the hair.

A further object is to provide a hairpin clip embodying pressure jaws particularly adapted to efficiently hold hair in pre-arranged form.

Another object is to provide a novel hairpin clip incorporating a helical spring and actuating elements emanating therefrom, whereby a highly efficient and firm spring action is attained.

A particular object is to provide a hairpin clip of combined helical spring and fulcrum type.

Further objects will be in part obvious and in part pointed out hereinafter.

The invention and the novel features thereof may best be made clear from the following description and the accompanying drawings, in which:

Figure 1 is a plan view of one form of hairpin 30 clip embodying the features of the present invention;

Figure 2 is an elevational view of the clip of Figure 1;

Figure 3 is an elevational view of the clip of Figure 1, showing the side opposite to that shown in Figure 2;

Figure 4 is a view corresponding to Figure 2, but showing the clip in open, hair-engaging position;

Figure 5 is a plan view of a further embodiment of the present invention;

Figure 6 is an elevational view of the clip of Figure 5;

Figure 7 is an elevational view of the clip of Figure 5, showing the side opposite to that shown in Figure 6, and

Figure 8 is a view corresponding to Figure 6, but showing the clip in open, hair-engaging position.

Referring to the drawings, in Figures 1 to 4 is shown a hairpin clip fashioned from an integral length of wire, resilient but capable of being bent to shape, and preferably of round cross-sectional shape. The central portion of the

2

length of wire is formed into a coil or helix 10, the inner diameter of which is preferably substantially equal to or slightly larger than the wire diameter, and must in any case, in the embodiment shown, be less than twice the wire diameter. One of the wire portions emanating from helix 10 is formed into short U-shaped actuating element or loop 11, terminating at the helix end opposite that from which it emanates, and adjacent to the helix axis. At the end of loop 11, the wire portion is bent through an acute angle, as at 12, and is then formed into the generally U-shaped pressure jaw indicated generally as 13, pressure jaw 13 in this manner being disposed in a plane angulated acutely to that of loop 11. Pressure jaw 13 terminates adjacent the end of helix 10 from which the loop 11 emanates, and in substantial alignment with the helix axis, and the wire portion emanating from the pressure jaw is bent inwardly at substantially a right angle to form end portion 14, positioned within the helix 10.

The wire emanating from the opposite end of the helix is formed into a complementary actuating loop 16, in a plane substantially parallel and adjacent to that of pressure jaw 13, and angulated acutely thereby to the plane of loop 11. Loop 16 is desirably of a shape and size corresponding to that of loop 11. At the end of loop 16, the wire portion, it will be seen, is disposed adjacent the helix end opposite to that from which it emanated, and offset slightly from the helix axis. The wire portion emanating from loop 16 is formed into the generally U-shaped pressure jaw 17, substantially coplanar with loop 16 and approximately complementary to jaw 13, and the wire portion terminates in the inwardly bent end portion 18, received within the interior of the helix. The outer portions of the actuating loops and pressure jaws may be either rounded or substantially rectangular with rounded corners, sharp corners being found uncomfortable to the user and detrimental to the hair.

Pressure jaw 13 adjacent bend 12 is desirably formed into a hump 19, whereby the humped portion of the pressure jaw is maintained in somewhat spaced relationship to pressure jaw 17 when the jaw ends are together. Pressure jaw 13 desirably is also transversely crimped, as shown, along its length from hump 19 substantially to the end 21 thereof. The complementary pressure jaw 17 is preferably of lesser width than jaw 13, and preferably is progressively narrowed along its length from the base

portion thereof to the jaw end 22. Pressure jaw 17 is also slightly longer than is jaw 13, so that the end 22 overhangs and normally engages end 21, thereby limiting the movement of the jaws into adjacency under the influence of helix 10. Helix 10, it will be readily understood, is formed so that its normal tendency is to effect angular divergence of the wire portions emanating therefrom, so that the helix exerts a spring action tending to angularly separate the actuating loops 11 and 16, and thereby urge the pressure jaws 13 and 17 extending from the loops into their normal closed, or adjacent, position.

It will be noted that by the above-described configuration of the pressure jaws, in normal closed position they tend to assume a slightly overlapping relationship, which has been found to effect an outstandingly efficient and permanent gripping action upon locks of hair engaged therebetween. This effect may be enhanced by displacing the jaw end 21 upwardly between its ends to provide a recessed portion 23, adapted to receive the narrower jaw end 22, whereby the side portions of the wider pressure jaw 13, especially at the low points of the crimping corrugations thereof, lie in substantially the same plane as the side portions of jaw 17. It will be readily recognized that with the pressure jaws so disposed relative to each other, locks of hair engaged therebetween are to a degree wrapped around the narrower pressure jaw 17, thereby assuming a curved configuration. This peculiar gripping action upon strands or locks of hair has been found to most effectively and efficiently hold the hair so engaged in its pre-arranged form.

The clip, when used, may be grasped by the loops 11 and 16 held between the fingers of the user's hand, and by forcing the loops toward each other, the pressure jaws will be pivoted into angularly spaced relationship, as illustrated in Figure 4. The clip may then be placed about the lock or strand of hair to be engaged thereby, and the loops thereupon released, whereby the jaws are caused by the spring action of helix 10 to assume their normal closed position, engaging the lock of hair therebetween and firmly holding the hair until the clip is removed. By reason of the hump 19, the outer portions of the pressure jaws will lie in approximately parallel planes when the jaws are separated slightly by a lock of hair, in this manner exerting substantially equal pressure along their operative length.

The spring action of the helix may be assisted and the clip greatly rigidified by insuring that each of the wire end portions 14 and 18 protrudes sufficiently from the helix to act as a fulcrum for the non-adjacent pressure jaw. This is conveniently accomplished, in the embodiment shown, by making each of the end portions 14 and 18 of a length substantially greater than one-half the axial length of the helix. By this expedient, it will be readily recognized that when the end portions are inserted into the helix into abutting relationship with each other, as shown by dotted lines in Figure 1, each will protrude a discrete distance from the end of the helix. If desired, the inner diameter of the helix may be substantially the same as the wire diameter, whereby the wire end portions 14 and 18 may be frictionally retained therein, in this manner assuring the desired positioning of the wire end portions and the protruding sections thereof. As an alternative, or to further insure fixed engagement of the wire end portions, the helix may

be slightly flattened or compressed after emplacement of the end portions therein in desired position. It will be evident that should the inner diameter of the helix be equal to or greater than twice the wire diameter, it will be possible for the end portions to overlap within the helix, making difficult the proper positioning of the wire end portions relative to the ends of the helix.

By reference to the drawings, it will be readily seen that in the opening of the pressure jaws by forcing the actuating loops 11 and 16 toward each other, the pressure jaws effectively pivot upon the outstanding sections of the wire end portions, the bend 12 pivoting upon end portion 18, and the wire section joining loop 16 to jaw 17 pivoting upon end portion 14. The wire sections pivoting upon the aligned end portions of the clip, it will be noted, are upon opposite sides of the helix axis, this feature particularly contributing to the firmness and rigidity of the clip in use.

In employment for securing locks or strands of hair in position during drying or other treatment, the embodiment of the invention shown in Figures 1 to 4 is desirably employed with the flat side thereof, that is, the side comprising loop 16 and jaw 17, adjacent the head of the user. Employed in this manner, the clip is quite comfortable and may be worn for long periods of time with no feeling of discomfiture or contact. The device being formed preferably of wire of round cross section, and embodying no sharp edges or curves, it may be employed with no damage to individual hairs or other strands engaged thereby, and may be position in and removed from the hair without scratching or otherwise damaging the scalp.

In Figures 5 to 8 is shown a further embodiment of the invention, of somewhat different form. In this embodiment, the central portion of the wire length is similarly formed into a helix 10, of proper internal diameter as previously set forth. The respective wire portions emanating from opposite ends of the helix are disposed in diverse planes angulated acutely relative to each other, constituting complementary actuating elements 24, as may be seen in Figures 5 and 6. The wire portions emanating from actuating elements 24 are bent sharply inwardly to opposite sides of a common plane intermediate the planes of the actuating elements, and the wire emanating from the inwardly bent portions 26 thus formed is fashioned into complementary, substantially parallel U-shaped pressure jaws 27 and 28. Pressure jaw 27 may be transversely crimped and correspond generally to the pressure jaw 13 of the modification previously described, and pressure jaw 28 is desirably formed into a longer and narrower shape, as in the case of pressure jaw 17 of the previous modification, and for similar reasons.

The wire portions emanating from the pressure jaws are bent outwardly to the plane of the actuating elements 24, forming matching bent portions 26, and thence in the planes of actuating elements 24 to the ends of the helix, forming matching actuating elements 24, the wire end portions 29 being inwardly bent and received within the ends of the helix. As previously stated, the helix may be flattened or compressed to retain the end portions, or may be of suitable diameter to frictionally retain them, although in this modification it is not necessary

that the end portions be long enough to abut within the helix, and they may be of lesser length, as indicated by dotted lines in Figure 5. Further, the outer ends of the pressure jaws may be flat, as shown, or the end of Jaw 27 may be recessed to receive the narrowed end of jaw 28.

The pressure jaws 27 and 28 are normally maintained in closed, clamping relationship as shown in Figure 6, with the outer ends of the jaws in engagement, by the spring action of the helix, exerted through the actuating elements emanating therefrom. The clip may be opened and the pressure jaws pivotally separated by pressure applied (as by the fingers) to the actuating elements 24, in a direction tending to move the pairs thereof toward each other, as illustrated in Figure 8. So held and opened, the clip may be inserted into the hair as previously described, preferably with the flat pressure jaw 28 thereof adjacent the scalp for obvious reasons, and then released to normally closed position to engage and retain a lock or strand of hair in the desired configuration. This modification of the invention is somewhat simpler to manufacture than is that of Figures 1 to 4, yet embodies similar advantages in substantially equal degree.

While particularly adapted for use as a hairpin clip, it will be understood that the device of this invention may be employed otherwise, as for general clipping and clamping purposes. For purposes requiring varying amounts of spring action and resistance to bending, it will be obvious that wire of correspondingly varying diameter and resilience may be employed.

It will thus be seen that there has been provided by this invention a structure in which the various objects hereinbefore set forth, together with many practical advantages, are successfully achieved. As various possible embodiments may be made of the mechanical features of the above invention, all without departing from the scope thereof, it is to be understood that all matter hereinbefore set forth or shown in the accompanying drawings is to be interpreted as illustrative, and not in a limiting sense.

I claim:

1. A hairpin clip constructed from an integral length of resilient wire, comprising a helix formed in the central portion of the wire, the inside diameter of said helix being substantially equal to the diameter of the wire, a pair of complementary jaw actuating elements formed in the wire portions emanating from said helix, and a pair of complementary U-shaped jaw members formed in the wire portions emanating from said actuating elements, said jaw members terminating in inwardly turned end portions frictionally retained within the ends of the helix.

2. A hairpin clip constructed from an integral length of resilient wire, comprising a helix formed in the central portion of the wire, the inside diameter of said helix being substantially equal to the diameter of the wire, a pair of complementary jaw actuating elements formed in the wire portions emanating from said helix, and a pair of complementary U-shaped jaw members formed in the wire portions emanating from said actuating elements, one of said jaw members being longer and narrower than the other and the wider of said jaw members being transversely crimped, said jaw members terminating in inwardly turned end portions frictionally retained within the ends of the helix.

3. A hairpin clip constructed from an integral

length of resilient wire, comprising a helix formed in the central portion of the wire, the inside diameter of said helix being substantially equal to the diameter of the wire, a pair of complementary jaw actuating elements formed in the wire portions emanating from said helix, said actuating elements lying in acutely divergent planes, the wire portions emanating from said actuating elements being bent inwardly to opposite sides of a common plane intermediate said actuating elements, and a pair of complementary U-shaped jaw members formed in the wire portions emanating from said inwardly bent portions, said jaw members being substantially parallel to said common plane, one of said jaw members being longer and narrower than the other and the wider of said jaw members being transversely crimped, the wire portions emanating from said jaw members being bent outwardly to the planes of said actuating elements, and the wire ends lying in the planes of said actuating elements and terminating in inwardly turned end portions frictionally retained within the ends of the helix.

4. A hairpin clip constructed from an integral length of resilient wire, comprising a helix formed in the central portion of said wire, the inside diameter of said helix being substantially equal to the diameter of the wire, and a pair of complementary U-shaped jaw members formed in the wire portions emanating from said helix, said jaw members terminating in inwardly turned end portions frictionally retained within the ends of said helix, one of said jaw members being longer and narrower than the other, the portions of said jaw members adjacent said helix being acutely divergent to constitute jaw actuating portions, said jaw members outward of said divergent portions being bent inwardly to cross each other, and the outer portions of said jaw members lying in substantially parallel, contiguous planes.

5. A hairpin clip constructed from an integral length of resilient wire, comprising a helix formed in the central portion of said wire, the inside diameter of said helix being substantially equal to the diameter of the wire, a pair of complementary actuating loops formed in the wire portions emanating from said helix and extending rearwardly therefrom in acutely diverse planes, said loops terminating adjacent the ends of said helix, and a pair of complementary U-shaped jaw members formed in the wire portions emanating from said loops and extending forwardly from said helix in substantially parallel planes, the wire ends emanating from said jaw members being turned inwardly into said helix and frictionally retained therein, each of the inwardly turned wire end portions being greater in length than half the length of said helix, whereby with their ends abutting inside said helix, each of said end portions protrudes sufficiently therefrom to constitute a fulcrum for the non-adjacent jaw member.

6. A hairpin clip constructed from an integral length of resilient wire, comprising a helix formed in the central portion of said wire, the inside diameter of said helix being substantially equal to the diameter of the wire, a pair of complementary actuating loops formed in the wire portions emanating from said helix and extending rearwardly therefrom in acutely diverse planes, said loops terminating adjacent the ends of said helix, and a pair of complementary U-shaped jaw members formed in the wire portions emanating from said loops and extending forwardly from said helix in substantially parallel planes, the wire ends emanating from said jaw members being turned

inwardly into said helix and frictionally retained therein, one of said jaw members being longer and narrower than the other and the wider of said jaw members being transversely crimped.

7. A hairpin clip constructed from an integral length of resilient wire, comprising a helix formed in the central portion of said wire, the inside diameter of said helix being substantially equal to the diameter of the wire, a pair of complementary actuating loops formed in the wire portions emanating from said helix and extending rearwardly therefrom in acutely diverse planes, said loops terminating adjacent the ends of said helix, and a pair of complementary U-shaped jaw members formed in the wire portions emanating from said loops and extending forwardly from said helix in substantially parallel planes, one of said jaw members being longer and narrower than the other and the wider of said jaw members being transversely crimped, the wire ends emanating from said jaw members being turned inwardly into said helix and frictionally retained therein, each of the inwardly turned wire end portions being

greater in length than half the length of said helix, whereby with their ends abutting inside said helix each of said end portions protrudes sufficiently therefrom to constitute a fulcrum for the non-adjacent jaw member.
